(57) **CLAIM**

The ornamental design for a handle for a mug or similar article, as shown and described.

DESCRIPTION

FIG. 1 is a top, front and right side perspective view of a handle for a mug or similar article showing my new design; FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken line illustration of the mug in the drawings depicts the environment in which the design resides and forms no part of the claim.
